END STANDARD FOR THEATER CHAIRS

Leo Jiranek, New York, N. Y., assignor to Heywood-Wakefield Company, Gardner, Mass., a corporation of Massachusetts

Application July 8, 1940, Serial No. 344,339

6 Claims. (Cl. 240—4)

This invention relates to improvements in end standards for theater chairs and it consists of the matters hereinafter described and more particularly pointed out in the appended claims.

The invention is more especially concerned with an end standard for a theater chair employed at one end of a row of chairs for providing a subdued illumination of the adjacent part of an aisle so that the lateral aisle, between adjacent rows of chairs, may be distinguished by a patron entering the darkened auditorium of the theater.

One of the objects of the invention is to provide an end standard structure of this kind and wherein the light rays from a light source may be cast straight downwardly or toward the front or toward the rear of the standard, as desired.

Another object of the invention is to provide an end standard structure including a shade or hood so associated with the light housing or well that it may be turned about an axis to direct the light in a plurality of directions and generally in the vertical plane of the end standard.

A further object of the invention is to provide an end standard structure including a source of light and a shade or hood for directing the light rays and which structure while simple to make and assemble, is easy to adjust and is efficient for its intended purpose.

Also, it is an object of the invention to provide an end standard structure and a light ray controlling hood or shade therefor which does not unduly project from the body of the standard and therefore will not cause a patron to bump against the same with probable injury while walking in the adjacent aisle.

The above mentioned objects of the invention as well as others, together with the advantages thereof will more fully appear as the specification proceeds.

In the drawing:

Fig. 1 is a view in side elevation of an end standard for a theater chair embodying the preferred form of the invention.

Fig. 2 is a horizontal sectional view through the end standard, on an enlarged scale, as taken on the line 2—2 of Fig. 1.

Fig. 3 is a fragmentary view in side elevation of a part of the body of the standard about its light well or housing.

Fig. 4 is a view in elevation of the inside of the hood or shade associated with the parts of the body of the standard appearing in Fig. 3.

Referring now in detail to that embodiment of the invention illustrated in the drawing, 10

indicates the upright body of the end standard as a whole and which is provided at its front and rear margins with curved finishing strips 11 and 12 respectively. At the top of the body 5 is an arm rest 13. The bottom ends of the finishing strips 11 and 12 are provided with feet 14 whereby the standard may be attached to a floor which is indicated by the line 15.

The body 10 of the standard is preferably 10 made from a suitable piece of sheet metal. A 15 rectangular opening 16 is formed in the bottom end portion of the body 10 midway between the finishing strips 11 and 12. A circular plate 10a is 20 suitably fixed to the outer face of the body 10 about the opening 16 and the edge of this plate forms an annular shoulder, the purpose of 25 which will appear later. A light receiving housing or well 17 (see Fig. 2) is so disposed upon the inner face of the body as to cover said opening 16. The housing or well is provided with lateral flanges 18—18 and in said flanges are 30 openings 19 that register with sets of openings 20—20 in both the body 10 and circular plate 10a respectively. A bracket 21 is fixed to one 35 of the walls of the housing or well so as to support a socket 22 that receives an electric light 23.

24 indicates a hood or shade for covering the opening 16 from the outer face of the body 10. 40 This hood or shade, which is circular in shape, has an outside diameter large enough to cover the openings 20 in and the plate 10a on the body 10. It includes a rim with an annular flange portion 25, adapted to fit upon the annular shoulder as provided by the edge of the plate 10a, a radial flange portion 26 and a concavo-convex central portion 27. A part of the central portion 27 is removed to provide a light escape opening 28 which is disposed to face downwardly when the hood or shade is in operative position upon the body 10.

The hood or shade 27 is provided on the inside of its marginal portion with a pair of opposed bosses 29 adapted to engage flatwise on the plate 10a. In each boss is a threaded opening 30 and said openings are disposed on the circle of the openings 20 in the body 10 of the end standard and in the plate 10a thereon so as to register therewith.

To assemble the parts described, the hood or shade 24 is placed upon the outer face of the body 10 with its annular flange 25 in bearing engagement on the shoulder as provided by the edge of the circular plate 10a and with the inner face of the lugs 30 engaged with the face of said

plate 10a. This positions the hood or shade 24 with respect to the opening 16 and in a manner whereby said hood or shade may be turned about its axis. With the bracket 21, socket 22 and bulb 23 arranged in operative relation in the housing 17, the latter is positioned against the inner face of the body 10 so that certain openings 19 in its flanges 18 register with certain openings 20 in the body 10 and plate 10a respectively. Screws 31 are then inserted through said registering openings 19 and 20 and are threaded into the openings 30 in the bosses 29 of the hood or shade 24, which has been turned about its axis to register the holes 30 in the lugs 29, with said screws 31. By tightening said screws, they securely hold both the housing or well and the hood or shade in operative position upon the inner and outer faces respectively of the body 10.

When the lamp 23 is burning, its rays are directed downwardly through the opening 28 in the hood or shade. Ordinarily the opening 28 in the hood or shade faces straight downwardly as appears in full lines in Fig. 1. However, by removing the screws from the openings 30 in the hood or shade, the shade may be turned about the edge of the plate 10a as a bearing into a position whereby the opening 28 is disposed to direct the light from the lamp 23 downwardly and slightly forwardly as indicated in dotted lines in Fig. 4.

When the hood or shade is disposed in the new position, the screws 31 are tightened up to hold the shade or hood in the newly adjusted position.

Obviously the parts may also be adjusted so that the light will be directed slightly in a rearward direction. The dash, double dot position (Fig. 4) illustrates the position of the parts for such action.

It is pointed out that instead of the two sets of openings 20 being formed in the body 10, arculate slots may be substituted therefor.

The improved end standard as described is simple in construction for economical production, is easily adjusted and is efficient for its intended purpose.

While in describing the invention, I have referred in detail to the form, arrangement and construction of the parts involved, the same is to be considered only in the illustrative sense so that I do not wish to be limited thereto except as may be specifically set forth in the appended claims.

I claim as my invention:

1. An end standard for a theater chair or the like embodying therein an upright body portion having an opening therein, means providing a housing mounted on one face of said body portion and opening at one end through said opening to the other face of said body portion, a source of light disposed in and carried by said housing, a shade mounted on said other face of said body portion and covering said end of said housing opening therethrough, said shade having an eccentrically positioned opening therein for the passage of light therethrough, and means accessible from the first mentioned face of the body portion for attaching said housing and said shade to said body portion, said means being operable so that said shade may be turned about an axis substantially perpendicular to the plane of said body portion to arrange said opening therein in different angular positions about said axis.

2. An end standard for a theater chair or the like embodying therein an upright body portion having an opening therethrough, means providing a housing on one face of said body portion to the rear of said opening, a source of light disposed in said housing, a circular shade on the other face of said body portion and covering the opening therein and having a circular flange part and a central part provided with an eccentrically positioned opening therein for the passage of light therethrough, means on said other face of said body portion enclosed by and upon which said flange part is engaged, and means for attaching said circular flange part and said housing to said body portion, said means being capable of being manipulated from said one face of said body portion so that said shade may be turned about an axis perpendicular to the plane of said body portion to arrange the eccentrically positioned opening in the shade in different angular positions about said axis.

3. An end standard for a theater chair or the like embodying therein an upright body portion having an opening therein, a casing on one face of said body portion about said opening and having flanges extending beyond said opening and engaged with said one face of said body portion, a shade on the other face of said body portion and covering said opening and having a circular margin engaged with and covering an annular shoulder on said other face about said opening, and also formed with an eccentrically positioned opening for the passage of light therethrough, and screws passing through said housing flange and said body portion and having threaded engagement in said circular margin of said shade for securing the said parts together in operative relation, said screws being operable to permit the turning of said shade about an axis perpendicular to the plane of said body portion to arrange said opening in said shade in different angular positions about said axis.

4. An end standard for a theater chair or the like embodying therein an upright body portion having an opening therein, a housing disposed upon one face of said body portion and having an open front communicating with the opening in the body portion, a shade disposed upon the other face of said body portion and covering said opening and having an eccentrically positioned opening therein for the passage of light therethrough, and means for attaching said housing and said shade to said upright body portion, said attaching means being capable of manipulation to permit a turning of the shade about its axis into different angular positions.

5. An end standard for a theater chair or the like embodying therein an upright body portion having an opening therein, an annular shoulder on the outer face of said body portion about said opening, a housing on the inner face of said body portion having an open front communicating with the opening in said body portion and enclosing a source of light, a shade on the outer face of said body portion and covering said opening and having an eccentrically positioned opening therein for the passage of light therethrough, said shade having an annular flange enclosing and journalled on said shoulder so as to be turnable adjustable therein and means for attaching said housing and said shade to said body portion, said attaching means being capable of manipulation to permit a turning of the shade about the axis of said shoulder and said flange into

different angular positions for said eccentrically positioned opening.

6. An end standard for a theater chair or the like embodying therein an upright body portion having a relatively large opening therein, means providing an annular shoulder on one face of said body portion about the opening therein, there being a plurality of smaller openings through said body portion and arranged on a circle concentric with the axis of said annular shoulder, a shade having an eccentrically positioned opening therein for the passage of light therethrough,

5 said shade having an annular flange-like portion engaged with and journalled on said shoulder, a light receiving housing on the other face of the body portion and having an open front communicating with the opening in said body portion and screws passing through parts of said housing and through certain of said smaller openings in said body portion and into parts of said shade for securing said housing and said shade to said body portion and for disposing said opening in said shade in the desired angular position.

LEO JIRANEK.
